ICE TRAY RELEASE MECHANISM

Sven W. E. Andersson, Evansville, Ind., assignor,
by mesne assignments, to Servel, Inc., Dover,
Del., a corporation of Delaware

Application October 27, 1933, Serial No. 695,398

5 Claims. (Cl. 62—108.5)

This invention relates to ice trays or the like for use in household refrigerators, in which water, desserts, or other matter, is adapted to be frozen.

Considerable difficulty is experienced in removing ice trays from the cooling units in which they are placed to have their contents frozen, due to formation of an ice bond between the tray and the shelf or other supporting structure, and until such ice bond is broken removal of the tray is impossible.

It is an object of the present invention to provide means for facilitating and simplifying the removal of ice trays after the contents of the same have been frozen.

Other objects and advantages will be apparent from the following description taken in connection with the accompanying drawing, wherein:

Fig. 1 is a front elevation of an ice tray and fragmentary cooling unit;

Fig. 2, a central longitudinal fragmentary section on the line 2—2 of Fig. 1;

Fig. 3, a central longitudinal fragmentary section of a modified construction; and

Fig. 4, a central longitudinal fragmentary section of a still further modified construction.

Referring to the drawing, an evaporator or cooling unit 10 of a household refrigerator, not shown, is refrigerated in any desired manner. The evaporator 10 is provided with a tray receiving compartment or compartments, in which an ice tray 11 is placed for freezing the contents of the same. The tray 11 rests on the lower horizontal portion or shelf of the cooling unit, the broad flat bottom of the tray being in thermal contact with the shelf in order to provide a good heat path for removal of heat by conductivity through the tray and shelf. When the tray is filled with water, moisture on the bottom of the tray freezes and forms an ice bond between the bottom of the tray and the shelf, which bond it is necessary to break before or at the time of removal of the tray. This breaking of the ice bond can be accomplished by insertion of a flat instrument, such as a knife or the like, between the tray and the shelf. However, as shown on the drawing, there are provided leverage devices by which the breaking of the above described ice bond may be accomplished.

As shown in Figs. 1 and 2, the ice tray 11 consists of a tray or receptacle body 12, and a tray front 13 having a handle or hand grip portion 14. The tray body 12 has its front end provided with two bent over extended portions or abutments, to which the tray front is secured by means of bolts or other fastening elements 15. This construc-

tion is provided at the time of stamping the tray, the material at each side of the tray being cut along the line 16 in order to provide a triangular reinforcement at each front outer corner of the tray.

The front of the tray is rolled over to provide an inverted trough or inverted U-shaped channel 17, and means is provided for exerting pressure between the shelf on which the tray is supported and such channel. A lever 18 has its lower end 10 provided with a foot 19, the heel of which is adapted to engage and rest upon the shelf of the cooling unit when the tray is inserted. The foot 19 is provided on its upper surface with a socket 20, in which rests the lower extremity of a lever 15 21. The lever 21 is in the form of a bar having its upper end provided with a rounded portion 21', for engagement in the channel 17. The lever 18 has its upper extremity bent to form a finger grip 22, disposed in a readily accessible position forwardly of the end of the grip 14 of the ice tray front. The hand grip portion of the tray front is provided with a slot 23 through which the lever 18 projects, the slot permitting reciprocation of the lever. 25

The parts are maintained in assembled relation when the tray is removed from its support, by means of a flat spring 24, which has its central portion imbedded in a slot in the lever, as shown, or otherwise attached thereto, the ends of the 30 spring 24 being provided with lateral portions 25, held in place by the fastening bolts 15. With this described construction the spring 24 normally maintains the parts in the position shown in Figs. 2 and 4, but allows the downward swinging of 35 the lever handle 22 to twist such spring. The bar 21 is confined near the longitudinal center of the tray between ears or other abutments 26, formed integrally with the bent over portion of the front end of the tray. 40

In the use of the above described construction the tray body 12 is filled with water or the like to be frozen, and inserted in the evaporator or cooling unit of the refrigerator with which the tray is used. When thus inserted the parts will 45 be in the relationship shown in Figs. 1 and 2. Heat will be removed from the tray bottom through the shelf, and any moisture between the tray bottom and shelf will be frozen, thus firmly uniting the parts. When it is desired to remove 50 the tray with its contents, the handle 22 of the lever 18 is swung downwardly, thus increasing the distance from the curved top of the lever 21 and the heel of the lever, and as the shelf is fixed, the upper end of the tray will be forced upwardly 55.

and break any above described ice bond. Release of the handle 22 allows the spring 24 to turn the parts to the position shown in Figs. 1 and 2, whereupon the hand grip 14 of the tray front can be grasped and the tray removed from the cooling unit.

Referring to Fig. 3, a lever 30 is provided with an operating handle 31 at its upper end, and is provided with a foot 32 at its lower end. To the heel of the lever is hinged a short lever or bar 33, which has its upper end mounted on pivot 34 beneath the curved tray flange. A spring 35 is provided for normally maintaining the lever 30 in its uppermost and inoperative position. In operation, when the handle 31 of the lever 30 is swung downwardly, the foot 32 and lever 33 are moved toward a straight line relation and the distance between the portion of the lever which engages the shelf 10 and the upper end of the lever 33 is increased, thus raising the front end of the tray from the shelf.

As shown in Fig. 4, a lever 36 is pivoted at 37 beneath the front tray flange, and a lever 38 is pivoted at 39 to the lever 36. The lever 38 will be inclined when the tray is inserted and have its lower end in contact with the evaporator shelf, wherefore swinging of the lever 36 about its pivot 37 will increase the distance between the lower extremity of the lever 38 and the pivot 37, thus raising the front end of the tray. The lever 36 is preferably curved to snugly conform to the outline of the hand grip portion of the tray front 14. Further, the lever is preferably of sufficient weight so that it will return by gravity to its normal position as shown in Fig. 4, and can be grasped and swung upwardly for performing the loosening operation. Instead of allowing the lever to return to normal position by gravity, a spring or other desired means can be used.

It will be obvious to those skilled in the art that various other changes may be made in the construction and arrangement without departing from the spirit of the invention, and therefore the invention is not limited to what is shown in the drawing and described in the specification, but only as indicated in the following claims.

What is claimed is:

1. In combination with an ice freezing receptacle and a refrigerated support therefor of a toggle device on the receptacle for breaking an ice bond between the receptacle and support comprising a pair of levers hinged together and attached to the receptacle in a manner to be operatively associated with said receptacle and support respectively when said receptacle is on said support, means for operating said device comprising a handle formed integrally with one of said levers for moving said levers toward a straight line position to exert a separation force between said receptacle and support.

2. In combination with an ice freezing receptacle and a refrigerated support therefor of a toggle device on the receptacle for breaking an ice bond between the receptacle and support comprising a pair of levers hinged together and attached to the receptacle in a manner to be operatively associated with said receptacle and support respectively when said receptacle is on said support, means for operating said device comprising a handle formed integrally with one of said levers operatively associated with said receptacle and arranged to be lifted for moving said levers toward a straight line position to exert a separation force between said receptacle and support. 5

3. In combination with an ice freezing receptacle and a refrigerated support therefor of a toggle device on the receptacle for breaking an ice bond between the receptacle and support comprising a pair of levers hinged together and attached to the receptacle in a manner to be operatively associated with said receptacle and support respectively when said receptacle is on said support, means for operating said device comprising a handle formed integrally with the one of said levers operatively associated with said support and arranged to be pressed downwardly for moving said levers toward a straight line position to exert a separation force between said receptacle and support. 10

4. The combination with an ice freezing receptacle, adapted to engage a refrigerated support therefor, of a toggle device on the receptacle for breaking an ice bond between the receptacle and such support; said device comprising a pair of levers hinged together and attached to the receptacle in a manner to engage said support when said receptacle is supported thereon, and means for operating said device comprising a handle formed integrally with one of said levers for moving said levers toward a straight line position to exert a separating force between said receptacle and support. 30

5. The combination with an ice freezing receptacle, adapted to engage a refrigerated support therefor, of a toggle device on the receptacle for breaking an ice bond between the receptacle and such support; said device comprising a pair of levers hinged together and attached to the receptacle in a manner to exert a force on the receptacle and support respectively when said receptacle is on said support, and means for operating said device comprising a handle formed integrally with the one of said levers exerting the force on said receptacle and arranged to be lifted for moving said levers toward a straight line position to exert such force and cause a separation between said receptacle and support. 45
